UNITED STATES PATENT OFFICE

LOUIS A. REHFUSS, OF PHILADELPHIA, PENNSYLVANIA

LOCOMOTIVE BOILER AND FIRE BOX

Application filed January 11, 1928. Serial No. 245,895.

My invention relates to a water tube locomotive boiler.

A purpose of my invention is to adapt a locomotive boiler to operate at higher pressures than have hitherto been safely possible by avoiding having a complete barrel waist or shell section under boiler pressure. I use water and steam-carrying drums and tubes that are all of small section as compared to that of the customary barrel or shell. The requisite thickness of metal in a high-pressure drum varies directly with the drum diameter and by making the drums smaller I enable them to withstand higher pressures and wholly or partially eliminate internal stay bolts.

A further purpose is to adapt a locomotive to get up steam more quickly than has hitherto been possible. I reduce the water volume of the boiler system so that less heat is required to get up steam and spread the water that is present throughout a number of relatively small drums and many water tubes located for efficient heating. Incidentally I obtain a great reduction in the potential explosive force of the locomotive by avoiding any large quantity of water in any single drum.

A further purpose is to use compound super-heating of the steam of a locomotive. Using compound engines I super-heat the steam exhausting from the high-pressure cylinder or cylinders before sending it to the low-pressure cylinder or cylinders and preferably make the low and high-pressure super-heater units counterparts upon opposite sides of the locomotive waist.

A further purpose is to provide water tubes that are preferably straight or substantially straight in the waist section of a locomotive boiler, tubes that are easily inspected and cleaned while in place, easily removable for replacement and adapted to maintain violent circulation of water and to provide upflow tubes that are moderately long.

A further purpose is to use substantially straight tubes in the waist section of a locomotive. I make the downflow tubes relatively large and short, substantially vertical

and preferably at the sides of the waist, and the upflow tubes in transverse rows across the waist between top and bottom headers.

A further purpose is to slope upflow tubes in the waist section of a locomotive rearwardly upwardly to make the flow of water in the tubes counter-current to that of the forwardly travelling hot products of combustion and to make the tubes adapted to engage sparks which comprise incompletely burnt particles of fuel so that such particles drop to the floor of the waist for complete burning.

A further purpose is to give tubes in the waist section of a locomotive an upward slope sufficient to insure rapid circulation and an angle with the vertical sufficient to make the tubes moderately long.

A further purpose is to roof and floor the waist section of a locomotive with upper and lower rows of transverse headers connected together by rows of upflow tubes and to provide the headers with hand-holes aligned with the individual upflow tubes for use in inspecting, cleaning or replacing these tubes.

A further purpose is to provide access to transverse headers roofing and flooring the waist section of a locomotive by means of a removable cover above the upper headers and a suitable repair space below the lower headers.

A further purpose is to provide a locomotive waist section with four horizontal drums relatively spaced sectionally at the upper and lower corners of a square, one at the top and bottom on each side of the waist and to line the flue intermediate the drums with rows of piping connecting the drums. I provide a wall of vertical downflow pipe connections between the upper and lower drums at each side, a floor of transverse headers between the bottom drums, and a roof of transverse headers between the upper drums.

A further purpose is to provide a locomotive with a desirable form of fire-box and combustion chamber, that has a particularly long flameway and is well adapted to effect complete combustion and to give efficient utilization of the heat of combustion.

A further purpose is to provide a locomotive with a water space frame comprising rearward and forward transverse chambers or heads at the rear and front ends of the fire-box respectively, bottom drums connecting the heads along each side of the fire-box, side top drums and an intermediate and higher steam chamber connecting into and extending forwardly from the upper head, 5 and rows of water tubing between the different drums. I provide water tube connections between each bottom water drum and the two top water drums that comprise a row of tubes from the bottom drum connecting alternately into the top drums on opposite sides 10 of the locomotive.

A further purpose is to partially heat-shield a steam drum over the fire-box and combustion chamber of a locomotive by means 20 of interlacing and reversely sloping sets of transversely extending water tubes below the drum. I thus shield the drum or drums from direct radiation from the combustion chamber and yet permit some circulation of hot 25 gases around the steam drum or drums to properly eliminate any moisture carried from the water drums into the steam drums.

A further purpose is to avoid water surging in long horizontal drums that are partially 30 filled with water and partially with steam. I provide by-passing pipe connection between different portions of the length of the drums and also may use suitable baffles across the interior of the drums at 35 spaced intervals. Such surging or temporary backing up in one end of a drum more than in the other may be incident to the locomotive changing its speed or to lesser extent to its going up or down hill.

40 Further purposes will appear in the specification and in the claims.

I have elected to show two only of the many different forms of my invention selecting forms that are efficient and practical 45 in operation and which will illustrate the principles involved.

Figure 1 is a vertical section of a locomotive structure embodying a preferred form of my invention and corresponds to section line 50 1-1 of Figure 2.

Figure 2 is a section to enlarged scale taken upon the line 2-2 of Figure 1, in the direction of the arrows, with some of the parts removed.

55 Figure 3 is a section to enlarged scale taken on the line 3-3 of Figure 1.

Figure 4 is a top plan view of Figure 1 with the cover removed and some other parts removed for greater clearness.

60 Figure 5 is a fragmentary left end elevation of structure seen in Figure 4 with some of the parts removed.

Figure 6 is a section taken upon the line 6-6 of Figure 4.

65 Figure 7 is a fragmentary detail, in part

section, showing connection between the bottom fire-box-drum and the rear water space header.

Figure 8 is a fragmentary perspective view of a bottom fire-box-drum.

70 Figures 9 and 10 are fragmentary views showing alternative arrangements of diagonal riser tubes and one form of super-heater section, respectively.

Like numerals refer to like parts in all figures.

Describing in illustration and not in limitation and referring to the drawings:

Describing first the structure shown in Figures 1 to 10.

80 Any design of locomotive has necessarily been limited by the dimensions of tunnels and by track gages, restricting height and width, permitting extension in length only. This has made application of water tubes to boilers difficult.

The main structure includes a fire-box portion 20 at the rear, a combustion chamber and flameway portion 21, immediately above and front of the fire-box, a water tube waist portion 22 in front of the flameway and a forward portion 23 containing super-heaters, engines, stack and piping between the super-heaters and engines and between the engines and the stack.

90 The steam and water system broadly include vertical rear and front heads 24 and 25, horizontal drums 32 and 33 at the bottom along the sides for the length of the system, horizontal drums 28 and 29 along the sides at the top, horizontal steam drums 30 and 31 at the top between and somewhat above the side drums at the top and numerous water tubes which substantially cover the walls and roof of the whole furnace up to the forward end of the waist portion and the floor of the waist and also include transverse rows of connections between the side drums at the top and the steam drums and piping from the steam drums to the super-heaters and from the super-heaters to the engines.

100 The rearward head 24 connects at the top into the rear ends of side water drums 28 and 29 and of the steam drums 30 and 31, and connects at the bottom into the water drums 32 and 33 which connect at their forward ends into the front head 25.

110 The heads are also connected together by the arch supporting tubes 34 which carry a usual brick arch 35 between fire-box and combustion chamber. The wall portions 36 and 37 of the front head that receive the lower ends of the arch supporting tubes are preferably sloped perpendicular to the ends of the entering tubes 34.

120 Adjacent rows of water tubes A and B connect from the top of each of the lower bottom water drums 32 and 33 respectively into the two top water drums, pipes B connecting the upper and lower water drums 130

that are upon the same sides and comprising downflow tubes while pipes A connect the upper and lower water drums upon opposite sides.

- 5 The adjacent rows of pipes A and B enter the lower drums along lines that are somewhat angularly offset, as best seen in Figure 2, and the pipes of each row are relatively spaced a distance substantially equal to the 70
10 pipe diameter so that the pipes from the lower water drums to the upper drums on the opposite sides of the locomotive are in substantial contact where they cross at 38, Figures 1 and 2, below the steam drums.
15 The steam drums 30 and 31 (Figures 1, 2 and 4) are fastened together and are effectively a single chamber. The smaller diameters incident to making the drums separate make them adapted to withstand higher pressures than would be the case if a single drum were used having the capacity of the combined units; moreover the vertical height of the top of the double drum form of steam chamber is somewhat lower than would be 80
20 the case with a single drum and this may be important in view of the need for limiting the height to that which may have proper clearance for tunnels.

I show a cleanout opening at 39 in the forward head of the water space frame.

It will be seen that the fire-box and combustion chamber walls comprise the B tubes and adjacent lower portions of the A tubes both extending upwardly from the lower 95
35 water drums and that the roof comprises the upper portions of the two rows of A tubes where they bend around from beneath the upper water drum on one side to the water drum on the other side.

40 The two rows of crossing A tubes are in substantial contact at 38 immediately beneath the middle of the steam drums and effectively shield the steam drums from direct radiation from the combustion chamber and 100
45 fire-box yet by reason of open spaces 38' permit reasonable circulation of gas up around the steam drums in order to maintain suitable heat around these drums.

The section immediately in front of the 50 forward head 25 of the water space frame comprises a flameway portion of the combustion chamber that is considerably longer at the bottom than at the top because of the upward and rearward slope of the water tubes 110
55 in the waist portion which immediately follows the flameway.

In the illustration the lower water drums in front of the forward head of the water space frame are shown in two sections, 40 and 41 respectively for the reason only that long pipe lengths are difficult to obtain. The rear ends of the first section 40 connect directly into opposite sides of the front of the head 25 and are connected together over the 115
65 bottom of the flameway by a succession of

pipes 42 (Figure 1) which serve to stiffen the structure and also afford additional heating surface.

Rows of tubes E and D extend from the lower water drums 40 to drums 28 and 29. They are in general very similar to the rows of tubes B and A respectively and perform the same function as they do but further forward in the combustion chamber.

The tubes E connect the upper and lower drums that are upon the same side, and may therefore be substantially straight while the tubes D connect those that are upon opposite sides and hence are bent to cross the chamber.

The space above the head 25 is protected at the sides and top by tubes C and C' which are quite similar in function to tubes A and D.

They cross the chamber and connect with one or other of the upper drums 28 and 29.

The steam drums 30 and 31 preferably stop short of an inclined tube section, later described, in order to permit withdrawal of the inclined tubes. The drums are connected at 43 into pipes 44 leading to the high-pressure 90
super-heater 45 placed at the front of the waist.

In the waist in front of the flameway portion 46 of the combustion chamber I place a series of rearwardly and upwardly sloping water tubes spaced transversely across the waist or barrel of the locomotive boiler.

The bottom drums 41 (Figures 1 and 3) are cross-connected by a succession of transverse headers 47. A similar series of transverse headers 48 is provided between the upper water drums 28 and 29, the series of headers between the upper drums being farther to the rear than those between the lower drums.

The corresponding upper and lower headers 47 and 48 respectively, are connected together by rows of inclined straight pipes 49 which are spaced along the length of the headers a sufficient distance to provide room for the passage of the hot products of combustion and slope rearwardly and upwardly by reason of the upper series of headers being spaced farther back than the lower series of headers. The pipes 49 form the inclined tube sections to which reference has previously been made.

Hand holes 50 are provided along each upper and each lower header in alinement with the sloping tubes. These holes, sealed by suitable covers 51, give access to tube interiors for inspection and cleaning and also give access for removal of old tubes and the insertion of new ones.

I show in Figure 3 one row only of transversely spaced rearwardly and upwardly sloping tubes 49 between each pair of corresponding headers.

Optionally, however, I may make the headers of size to receive more than one row of tubes, as two or more rows, and illustrate 130

this in Figure 9, where I show headers 48' and 48² each provided with two rows of tubes 49' connecting with corresponding lower headers not shown.

5 The headers are available for inspection, repairs or the like at the top by lifting a removable covered plate 52 and at the bottom from within a repair space 53 which is normally closed by a door 54.

10 It will be understood that the headers 48 at the top preferably form what is substantially a roof for the main flue of the furnace, successive headers being substantially in contact with one another. The corresponding lower headers 47 form what is substantially a floor of the furnace.

The sloping tubes may be put into place after the tubular frame work including the upper and lower water drums and transverse 20 headers have been installed and properly fastened together into a single structure, the tubes sliding down from the top through the upper hand holes 50.

The series of pipes 49 between the transverse headers 47 and 48 are upflow pipes and the corresponding downflow pipes are straight pipes 55 preferably larger than pipes 49. The pipes 55 make vertical connection between the upper and lower water drums 20 on each side. They are less efficient heaters by reason of their larger size and hence become down-flow pipes. Pipes 55 are also masked by super-heater pipes, as seen in Figure 3.

35 I have shown one downflow pipe 55 at the end of each header although obviously there is no direct connection between the number of transverse headers and the number of vertical downflow pipes between the upper and lower drums at the sides.

Preferably the downflow pipes line the sides and are suitably larger than the upflow pipes. The upper side drums 28 and 29 are partially filled with water and partially filled 45 with steam, a normal water level being about that indicated at 56, Figure 2.

Obviously during periods of speed acceleration and periods of going up hill there is some tendency for the water in the drums 28 and 29 to pile up between the forward ends 50 of the side drums and the steam drums and thereby to produce water throttling or possibly even momentary water sealing between the steam generated at the front of the locomotive and the steam drums, and to avoid danger of heavy slugs of water being carried 55 into the steam drums I preferably provide by-passing pipes 57. These pipes extend along and somewhat above the respective top 60 water drums, connecting with the drums at different points 58 and desirably also connect into the steam drums at 59 and into the steam supply lines at 60 before the superheater, (Figure 4).

65 These pipes prevent danger of fluctuation

in pressure due to any water surging in the water drums and greatly lessen any danger of water slugs being carried over into the steam drums.

I may also provide transverse baffles or dams 61 at intervals along the water drums. As indicated these dams extend upwardly 70 from the bottom so as to prevent any material longitudinal flow of water in the drums without affecting seriously the flow of steam 75 which takes place above the dams rearwardly along the water drums to the steam drums, and from the steam drums forwardly through pipes 44 to the high pressure super-heater 45.

The pipes 44 from the steam drums 30 and 31 to the high pressure super-heater header 45 extend from the forward ends of the respective steam drums diagonally downward to run along the lower sides of the water drums just inwardly from the downflow pipes 55 between the upper and lower water drums.

While I have illustrated these steam pipes as leaving the steam drums from the forward ends of the drums it is obvious that if desired they may leave the steam drums from the lower side, an arrangement which might have some advantage in that it would permit the row of transverse headers 48 between the upper side drums 28 and 29 to begin further rearwardly and in that it avoids an open space 63, Figure 4, between the forward ends of the steam drums and the first transverse header 48.

In the figures I show a riveted construction of drums. For pressures much above 500 lbs. it will usually be advisable to use a forging construction.

The super-heaters may be of any suitable type and their indication on the drawings is intended as a conventional one for any suitable super-heaters.

Obviously if desired only the high-pressure steam supply may be subjected to super-heating but I prefer to super-heat also the steam that leaves the high-pressure cylinder or cylinders of a compound unit before it goes to the low-pressure cylinder or cylinders.

As best seen in Figures 1, 4 and 5, the steam generated chiefly in the different upflow tubes, A, D, C and 49 and headers 48 initially enters the upper side drums 28 and 29 whence it flows through suitable connections 64 into the steam drums 30 and 31. It will be seen that steam generated in the waist portion of the locomotive flows rearwardly along the upper water drums to enter the steam chambers 30 and 31.

From the steam drums the steam flows forwardly through pipes 44 into a header 65 which connects at 66 into the high-pressure side of the super-heater.

High-pressure super-heater pipes 67 ex- 123

tend rearwardly and forwardly in the space below the drum 28 and between the down-flow pipes 55 and the upflow pipes 49 as best seen in Figure 3 to return to the body portion 45 of the super-heater whence it flows by pipe 68 to the high-pressure cylinder or cylinders of the compound engine unit.

In the illustration there is only one high-pressure cylinder 69 shown and two low-pressure cylinders 70 and 71, the high-pressure cylinder being shown in the middle and the low-pressure cylinders at the sides. The indication of the piping and of these cylinders is intended as a conventional one for any suitable piping and suitable cylinders.

The exhaust from the high-pressure cylinder flows through pipe 72 to the body portion 73 of the low-pressure super-heater, then to the super-heater coils 74 which except for possible larger sectional pipe areas due to the greater volume of the low-pressure steam may be counterpart to the high-pressure coils 67, and are located on the opposite side of the locomotive below the drum 29.

Passing through the coils 74 the super-heated low-pressure steam flows back to the body of the super-heater and from there through pipe 75 and branch pipes 76 and 77 to the low-pressure cylinders 70 and 71.

Discharge from the low-pressure cylinders takes place through pipes 78 and 79 into an outlet nozzle 80 directed upwardly into the stack.

A feed water connection is shown at 81 (Figure 4) into one of the bottom side drums. There should be suitable provision for maintaining substantially definite quantity of water in the system, but this forms in itself no part of the present invention and has therefore not been shown.

The flameway portion immediately after the fire box provides a space for more complete combustion of the hot products before they are cooled by engagement with the transverse tubes 49.

This flameway or additional combustion space between the fire box and the transverse tubes 49 is one of the advantageous features of my invention and very materially increases the effectiveness of combustion.

It will be seen that the flameway portion of the waist is provided with tubular roof, tubular floor and tubular walls but does not have the transverse rows of upwardly and rearwardly extending water tubes across the interior section of the flue.

The word "flameway" as used in the specification and claims thus means a portion of flue beyond the fire box that is open in that it does not have water tubes extending transversely across its interior.

In view of my invention and disclosure variations and modifications to meet individual whim or particular need will doubtless become evident to others skilled in the

art, to obtain all or part of the benefit of my invention without copying the structure shown, and I, therefore, claim all such in so far as they fall within the reasonable spirit and scope of my invention.

Having thus described my invention what I claim as new and desire to secure by Letters Patent is:

1. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box and having substantially vertical water tube connections with the upper drums, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower drums to one another at near intervals along a forward portion of their length and rearwardly and upwardly inclined water tubes connecting said upper headers to said lower headers, the inclination of said tubes providing a combustion chamber between the fire box and said water tubes.

2. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box and having substantially vertical water tube connections with the upper drums, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower drums to one another at near intervals along a forward portion of their length, rearwardly and upwardly inclined water tubes connecting said upper headers to said lower headers, the inclination of said tubes providing a combustion chamber between the fire box and said

water tubes.

water tubes, a steam drum over the fire box intermediate, higher than and connected to the said upper drums, and super-heater coils at both sides of the section outwardly of the inclined water tubes and connected with the steam drum.

3. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box and each having water tube connections at the top alternately to the upper drums, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower drums to one another, at near intervals along a forward portion of their length, rearwardly and upwardly inclined water tubes connecting said upper headers to said lower headers, the inclination of said tubes providing a combustion chamber between the fire box and said water tubes, a pair of steam drums side by side over the box and intermediate and higher than the upper side drums and conduit connections between the steam drums and the upper side drums.

4. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box a row of water tubes from each bottom water drum up along the sides of the box and alternately connecting respectively into the upper drum on the same side and the upper drum on the opposite side, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower

drums to one another at near intervals along a forward portion of their length, rearwardly and upwardly inclined water tubes connecting said upper headers to said lower headers, the inclination of said tubes providing a combustion chamber between the fire box and said water tubes, a pair of steam drums side by side over the box and intermediate and higher than the upper side drums and conduit connections between the steam drums and the upper side drums.

5. In a locomotive comprising a water tube type of boiler and a smoke box forwardly thereof and successive lengths of the boiler including from the rearward end thereof a fire box, a combustion chamber and a flue section, horizontal side drums along the top and bottom of the boiler substantially for the length thereof, the bottom drums extending further forward than the top drums, a row of headers forward of the fire box connecting the bottom side drums to one another and forming a furnace floor of closely spaced headers from the fire box to near the forward end of the lower side drums, a row of other headers forward of the fire box connecting the top drums to one another and forming a furnace ceiling of closely spaced headers from the fire box to near the forward end of the upper drums, rows of rearwardly and upwardly sloping upflow tubes connecting the transverse upper headers with the more rearward transverse lower headers, and a row of substantially vertical downflow tubes along each side forward of the fire box connecting the upper and lower side drums, the connection between the more rearward upper transverse headers with the more forward lower transverse headers leaving a flue space beyond the fire box substantially free from the connecting tubes across the area of the section.

6. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box and having substantially vertical water tube connections with the upper drums, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower drums to one another at near intervals along

a forward portion of their length, rearwardly, upwardly inclined water tubes connecting said upper headers to said lower headers, the inclination of said tubes providing a combustion chamber between the fire box and said water tubes, a steam drum above the fire box higher than and having connections with the tops of the upper side drums and side steam supply pipes from the forward end of the steam drum extending forwardly lower than the upper horizontal side drums in combination with side steam pipes higher than the said upper drums and connected into the tops thereof at spaced intervals along their length and into the steam drum at the rear.

7. In a locomotive comprising a water tube type of boiler and a smoke box forwardly thereof and successive lengths of the boiler including from the rearward end thereof a fire box, a combustion chamber and a flue section, a pair of horizontally spaced upper drums extending substantially the length of the boiler, a pair of horizontally spaced lower drums extending substantially the length of the fire box and having substantially vertical water tube connections with the upper drums, a transverse water leg connecting the forward ends of the lower drums, a pair of horizontally spaced lower drums extending forwardly of the fire box beyond the forward ends of the upper drums and connected at their rearward ends into said transverse water leg, headers connecting said upper drums to one another at near intervals along a portion of their length forwardly of the fire box, other headers connecting said second mentioned pair of lower drums to one another at near intervals along a forward portion of their length and rearwardly, upwardly inclined water tubes connecting said upper headers to said lower headers, the inclination of said tubes providing a combustion chamber between the fire box and said water tubes, a steam drum above the fire box higher than and having connections with the tops of the upper side drums and side steam supply pipes from the forward end of the steam drum extending forwardly lower than the upper horizontal side drums in combination with side steam pipes higher than the said upper drums and connected at intervals along their length into the tops thereof and dams at spaced intervals across the interior of the upper side drums extending upwardly from the bottom and leaving spaces for the rearward flow of steam to the steam chamber.

LOUIS A. REHFUSS.
